UNITED STATES PATENT OFFICE.

JOSEPH A. MASONICK, OF LAKE BLUFF, ILLINOIS, ASSIGNEE TO J. A. MASONICK COMPANY, OF LAKE BLUFF, ILLINOIS, A CORPORATION OF ILLINOIS.

DISHWASHING MACHINE.

Application filed May 6, 1921. Serial No. 467,289.

To all whom it may concern:

Be it known that I, JOSEPH A. MASONICK, a citizen of the United States, residing at Lake Bluff, in the county of Lake and State of Illinois, have invented certain new and useful Improvements in Dishwashing Machines, of which the following is a specification.

This invention relates to dish washing machines and aims primarily to provide a machine which will be simple in construction, easy to manipulate and efficient and reliable in operation.

Another object of my invention is to provide a machine which shall be so constructed that a tray of dishes may first be disposed in a washing receptacle where the dishes are washed by a circulation of water in the receptacle, then the tray may be slid longitudinally of the machine into a rinsing compartment where the dishes are subjected to sprays of rinsing water delivered upwardly and downwardly in the chamber, and then the tray may be slid still further longitudinally of the machine out from the rinsing chamber onto a drain board, where the dishes are permitted to drain and dry.

Another purpose of the invention is to provide a machine which can be entirely controlled and operated from one side thereof, one in which all the manipulating devices are readily accessible to the operator and one in which the various parts are so mounted as to be adequately protected, but at the same time easily accessible for purposes of repairs and the like.

Another object is to provide a machine which not only serves as a dish washer and rinser, but also as a sink in which greasy pots, pans, etc. may be manually scrubbed, and in and about which other operations customarily performed in a kitchen sink may be conducted.

Other objects and many of the inherent advantages of this invention should be readily appreciated as the same becomes better understood by reference to the following description when considered in connection with the accompanying drawings.

Referring to the drawings—

Fig. 1 is a longitudinal sectional view of a machine embodying my invention;

Fig. 2 is a transverse sectional view thereof taken through the rinsing chamber and receptacle;

Fig. 3 is a similar view through the washing receptacle;

Fig. 4 is a plan view of the machine;

Fig. 5 is a plan view of the dish tray on an enlarged scale; and

Fig. 6 is a transverse sectional view through the tray shown in Fig. 5.

From an inspection of the drawings it will be observed that my machine comprises primarily a frame consisting of the end members 7 and 8 which are connected by longitudinally extending members 9 forming a table or support for the various mechanisms to be later described. In the upper portion of this frame there is mounted an elongated horizontally extending tank 11 divided intermediate its ends by a transverse partition 12 dividing the tank into a washing receptacle or sink 13 and a rinsing receptacle 14. While this tank may be of any preferred shape in cross-section, the side walls thereof preferably incline downwardly and inwardly, so that the bottoms of the receptacles are narrower than the tops, as will be apparent from Figs. 2 and 3. At each side the tank is provided near its top with an inwardly extending dish tray supporting ledge 15 upon which a tray of dishes may be positioned and slid longitudinally of the machine from a position over the washing receptacle to a position over the rinsing receptacle.

Upon the table or support 9 beneath the tank there is mounted an electric motor 16, the longitudinally extending drive shaft of which is preferably directly connected with a rotary washing pump 18, the intake pipe 19 of which communicates with the washing receptacle, preferably through the bottom thereof, and its intake end is equipped with a screen 21 to exclude solid matter from entering the pump. The delivery pipe 22 from this pump extends upwardly into the tank and terminates in a longitudinally disposed outlet 23 from which the water is delivered in a longitudinal direction in the washing receptacle. It will be apparent, therefore, that by delivering the water at 23 and withdrawing it from the receptacle

through the pipe 19 a continuous circulation of washing water in this receptacle is maintained so that the dishes carried by the tray 24, indicated in dotted lines in Fig. 1, are subjected to the action of the circulating water to remove the food particles, etc. adhering thereto.

Above the rinsing receptacle, I have provided a rinsing chamber 25 preferably constructed of sheet metal having solid side walls and top, the end walls, however, being formed by doors 26 and 27 adapted to slide vertically in suitable guideways 28 and 29 respectively, and to facilitate the opening of these doors they are each counterbalanced by a weight 31 adapted to travel vertically in the housing 32 at the back side of the machine, these weights being connected with their respective doors by chains 33 which are trained over pulleys 34 and 35 mounted upon the top of the chamber. Beneath the rinsing receptacle upon the support 9 there is mounted a rinsing pump 36, the intake pipe 37 of which opens into the rinsing receptacle through or near the bottom thereof and this pump is equipped with two delivery pipes 38 and 39 respectively, through which rinsing water is delivered to the chamber 25. The pipe 39 is horizontally extended as shown in Fig. 2 and is equipped with one or more upwardly discharging spray nozzles 41 which are adapted to deliver sprays of water upwardly over the dishes disposed in the tray 24 directly over these nozzles. The pipe 38 is continued upwardly at the back of the machine and provided with a horizontal extension 42 to which is connected a delivery pipe 43 opening into the rinsing chamber through the top thereof. For the purpose of causing the water discharged from the pipe 43 to be delivered in a plurality of streams or sprays, I have mounted in the upper portion of the rinsing chamber a perforated tray 44 which is removably carried upon a pair of supporting rods 45, or if preferred, one end thereof may be supported by arms or brackets 46 fixed to the door frame of the chamber, as shown in Fig. 1.

For the purpose of supplying clean fresh water to the rinsing receptacle when required, the pipe 42 is extended across the top of the machine, as shown in Fig. 4, and is then looped back and connects through a pipe 47 with the city water supply pipe indicated in Fig. 4 by 48. A hand valve 49 accessible from the front of the machine is disposed in the loop and when this valve is opened water will be delivered to the rinsing receptacle through the pipe 43 and also through pipes 38 and 39, as will be apparent. For the purpose of supplying the washing receptacle with clean water a faucet 51 connected by a pipe 52 with the water supply pipe 48 is disposed over the wash-

ing receptacle, as shown in Figs. 1 and 4. The receptacles are equipped with combined overflow and drain pipes 52 and 53 respectively, their upper ends being disposed at the maximum desirable water level and their lower ends being loosely seated in the drain pipes 54 and 55 so that when the overflow pipes are lifted the receptacles may be drained through their respective drain pipes which are both connected with a common drain delivery pipe 56 leading to the sewer.

The washing pump 18, as previously explained, is preferably directly connected with the motor drive shaft 17, but the rinsing pump 36, while mounted in axial alignment with this shaft, is preferably connected thereto through the intermediary of a clutch 57 which is controlled from a hand lever 58 disposed at the front of the machine so that the rinsing pump may remain idle while the batch of dishes is being washed in the washing receptacle and need be thrown into operation only when the dishes have been placed in the chamber 25 for purposes of rinsing. The motor 16 may be controlled by a switch of usual construction which for convenience is preferably mounted at the top of the machine near the front side thereof, such a switch being indicated by reference character 58', and the wire to this switch is preferably disposed in a conduit 59 for purposes of safety and protection. In order that the water in the respective receptacles may be heated to any desired temperature, I provide beneath the washing receptacle one or more gas burners 61, the gas supply to which is furnished through a pipe 62 from the usual supply, and similarly beneath the rinsing receptacle there is mounted one or more burners 63. Obviously, by means of these burners any desired temperature of the washing and rinsing waters may be produced and maintained.

At the side of the rinsing chamber opposite to the washing receptacle there is mounted a drain board 64 inclined from its outer edge downwardly toward the rinsing receptacle into which the water drains and, as will be evident from Fig. 1, the inner edge of this board is in substantial alignment with the tray supporting ledges 15 so that a tray of dishes may be simply slid from the rinsing chamber out onto the drain board when the door 27 is opened without the necessity of lifting the tray. The tray itself may be of any approved construction, but I have found that one convenient form is that shown in Figs. 5 and 6, in which the tray is shown as consisting of a box-like structure having inclined side walls connected near their bottom by a series of transversely extending wooden rods 65, the vertical end walls of the tray being connected preferably by a plurality of rows of

longitudinally extending wooden rods 66. The dishes may be positioned in this tray vertically, or preferably at an inclination to the vertical, so that their surfaces are 5 more fully exposed to the action of the rinsing jets in the rinsing chamber. It will be observed that the length of the tray is such that when disposed transversely of the sink the ends of the tray will be supported 10 upon the ledges 15, but when disposed longitudinally of the sink the tray will enter between the ledges so that it may be deposited on the bottom of the tank, receptacle, or sink as it may be termed in the claims, 15 as shown in Figures 1 and 3.

In the operation of my machine the requisite quantity of water may be supplied to the washing and rinsing receptacles by opening the faucet 51 and the valve 49. 20 This water may then be brought to the requisite temperature by the burners 61 and 63 and preferably a quantity of soap is added to the water in the receptacle 13 to facilitate the washing. A tray loaded with 25 dishes is now deposited in the washing receptacle, as shown in Fig. 3, whereupon the washing pump 18 is started by turning on the motor 16 through the switch 58. The water in the washing receptacle is thus 30 caused to circulate around the dishes so as to remove the food particles and the like adhering thereto. After the washing operation has proceeded for the requisite length of time the tray is lifted from the washing 35 receptacle, turned through an angle of 90 degrees to dispose its ends upon the supporting ledges 15, and is thereupon pushed longitudinally of the same into the rinsing receptacle, the doors of which are then 40 closed.

The pump 36 is then started by throwing in the clutch 57 through the medium of the lever 58 and the rinsing water withdrawn 45 from the rinsing receptacle by the pump is discharged upwardly against the dishes from the nozzles 41 and downwardly over the dishes from the tray 44. When the dishes have been sufficiently rinsed, the door 27 is 50 opened and the tray is pulled out of the chamber onto the drain board 64, where it is permitted to stand until the dishes have thoroughly drained and dried. In the meantime, during the rinsing operation another tray-load may be washed and this load 55 is then moved into the rinsing chamber and another batch deposited in the washing receptacle, so that three batches of dishes may be progressively handled simultaneously, one batch being washed, another rinsed 60 and a third dried all simultaneously. After the table dishes have been washed, the greasy pans, pots and other cooking utensils may be washed and manually scrubbed in the sink in the same washing water which is 65 already heated. The necessity of heating

other water for this purpose and of besmirching another sink with these utensils is therefore obviated. The sink may at any time be used as an ordinary kitchen sink.

It will be apparent from the foregoing 70 that I have provided a machine which is simple in construction, efficient and rapid in operation, one which can be easily manipulated and which is durable and reliable, and while I have shown and described a preferred embodiment of my invention it will be obvious that the various details are capable of wide modification without departing 75 from the spirit of the invention as defined in the following claims. 80

I claim:

1. In a dish washing machine, the combination of a receptacle provided near the top with longitudinally extended supporting ledges, a dish tray adapted when disposed longitudinally of the receptacle to be submerged in the water therein and when disposed transversely to be slidably supported on said ledges, means for circulating the washing water in said receptacle around the submerged dishes in said tray, a rinsing chamber at one end of said receptacle into which a tray of dishes may be slid along said ledges, a rinsing receptacle beneath said chamber, means for delivering the rinsing water from said receptacle upwardly and downwardly against the dishes in said chamber, doors for closing the sides of said chamber, and a drain board at the opposite side of said chamber from said receptacle onto which the dishes may be slid from said chamber. 90

2. In a dish washing machine, the combination of a receptacle, means for circulating water within said receptacle, a dish tray adapted when disposed longitudinally of the receptacle to be submerged in the water therein and when disposed transversely to be slidably supported by the receptacle above the water level therein, a rinsing chamber at one end of said receptacle into which a transversely disposed tray of dishes is adapted to be slid from the receptacle, means for delivering rinsing water upwardly and downwardly against the dishes in said chamber, doors for closing the sides of said chamber, and a drain board at the opposite side of the chamber from the receptacle onto which the dishes may be slid from said chamber. 105 110

3. In a dish washing machine, the combination of an elongated tank, divided transversely into a washing receptacle and a rinsing receptacle, dish tray supporting ledges extending longitudinally of the tank near the top thereof, a dish tray proportioned to be positioned in said washing receptacle when disposed longitudinally thereof and to rest upon said ledges when disposed transversely thereof, a rinsing chamber 120 above said rinsing receptacle including a 125

door through which said tray may be slid along said ledges from the washing receptacle into the rinsing chamber, and a drain board at the opposite side of said chamber adapted to receive the dishes from said chamber.

4. A kitchen appliance comprising, a tank, and an article receptacle constructed and arranged to be submerged beneath the level 10 of the top of said tank when bodily disposed in one direction with respect thereto and to rest slidably upon fore and rear portions of the walls of said tank for horizontal movement thereon when disposed in a direction 15 at right angles to the first said direction, and an inclosed chamber adjacent said tank and constructed and arranged to receive said receptacle when the latter is moved horizontally along said edge portions.

5. A kitchen appliance comprising in combination, an open tank portion to receive articles for preliminary washing and adapted to serve as the usual kitchen sink, the 20 fore and rear walls of said tank forming ways, an article receptacle constructed and arranged to be submerged beneath the level of the top of said tank when disposed in one direction therein and to rest slidably upon 25 said ways when disposed in a direction at right angles to the first said direction, and a closed chamber in conjunction with said tank, constructed and arranged to receive

said receptacle when slid horizontally along said wall portions.

6. A kitchen appliance comprising, an open tank portion to receive articles for preliminary washing and adapted to perform the functions of the usual kitchen sink and the walls thereof providing ways, an article 40 receptacle adapted to be disposed in said tank and constructed and arranged to be submerged beneath the level of the top of said tank when disposed in one direction therein and to rest slidably upon fore and 45 rear portions of the walls of said tank for horizontal movement thereon when disposed in a direction at right angles to the first said direction, a chamber having doors diametrically opposed in a direction parallel to 50 said ways, and a drain board disposed adjacent the opposite side of said chamber adapted to receive said receptacle therefrom.

7. In combination, a kitchen receptacle capable of performing the functions of a sink and dish washer comprising a tank in which to preliminarily wash dishes disposed therein, a normally closed rinsing chamber adjacent thereto, and common side walls for said tank and chamber lying in substantially 60 the same horizontal plane, said side walls constituting a means for slidably transferring dishes in bulk from said receptacle horizontally into said chamber.

JOSEPH A. MASONICK.
